UNITED STATES PATENT OFFICE.

FERDINAND PIASZEK, OF SAGINAW, MICHIGAN.

HEADLIGHT REFLECTOR.

Application filed October 18, 1923. Serial No. 668,374.

To all whom it may concern:

Be it known that I, FERDINAND PIASZEK, a citizen of the United States, residing at Saginaw, in the county of Saginaw and State 5 of Michigan, have invented certain new and useful Improvements in Headlight Reflectors, of which the following is a specification.

This invention relates to a headlight reflector, and particularly to the construction of a reflector adapted to project the rays from an illuminating medium into a forward and downward path in advance of the reflector.

15 In previous constructions of conical reflectors the rays have been concentrated and projected forwardly in a light beam of considerable intensity but the rays from the upper portion of such a beam have a constant tendency to an upward projection which produces a glare and limits the amount of light concentrated upon the road in advance of the vehicle upon which the lamp is disposed, which results in a serious inconvenience to an approaching driver and fails to properly illuminate the path of travel of the vehicle.

The present invention comprises a novel and improved construction of conical body 30 having a portion of its lower wall provided with a supplemental reflecting surface disposed in the lower inclined wall in alignment with the source of illumination so that the light rays therefrom are directed to the 35 curved supplemental reflecting surface and thence projected outwardly and downwardly from that portion of the reflector from which they would be otherwise projected upward so that the area directly in front 40 of the lamp has the main light rays projected in a downward path.

Another object of the invention is to present an improved construction of conical body terminating at its apex in a portion 45 having a concentric wall and a sleeve disposed to surround said wall and provided with a central collar to support a lamp socket in a plane parallel with the upper wall of the reflector which is disposed in a substantially horizontal plane.

Other and further objects and advantages of the invention will be hereinafter set forth and the novel features thereof defined by the appended claims.

55 In the drawing:—

Figure 1 is a longitudinal vertical section of the reflector;

Figure 2 is a front elevation; and

Figure 3 is an enlarged detail section on line 3—3 of Figure 1.

60

Like numerals refer to like parts throughout the several figures of the drawing.

The numeral 10 designates the reflector which may be of any desired size and is of a generally conical configuration with its interior face highly polished or provided with a reflecting surface throughout its entire length. This conical body is arranged so that the upper surface 11 thereof is disposed in a substantially horizontal plane 70 and the front face 12 at a right angle thereto. The lower segment 13 of the reflector is sharply inclined downward at an angle to the upper face 11 and forms a wall of greater length than the upper wall of the reflector. The structure thus comprises a cone having its walls of increasing length from the apex from a point at the top of the cone when disposed in a horizontal plane. The apex 14 of such cone is formed 80 with a concentric portion 15 adapted to receive and support a lamp socket 16 in any preferred manner in order to dispose the lamp 17 carried thereby in a substantially horizontal plane parallel with that of the 85 upper surface of the reflector. A desirable means for thus supporting the socket comprises the sleeve 18 embracing the concentric portion 15 of the cone and provided with a collar 19 to support the lamp socket 90 16. This sleeve may be secured in position by any desired means such as the projecting portions 22 which form an interlocked connection. The forward portion 13 of the cone is also provided with an angular flange 95 20 by which the reflector is suitably secured within the usual lamp casing.

An important object of the present invention is to provide a supplemental reflecting surface in substantial alignment or 100 in focus with the lamp member 17, and this is accomplished by the depressed parabolic reflecting portion 21 which may be formed in the lower inclined wall 13 of the reflector or attached thereto and is so disposed as 105 to collect and direct the downward light rays from the center of the lamp into outward paths which effect a light beam below the top of the reflector projected directly upon the road. This supplemental 110

reflector is disposed at the portion of the reflecting surface from which an outward and upward ray is usually projected in a plane which avoids the upper face of the 5 reflector, with the result that the light beam extends to a point above the lamp and produces the glare which the present invention avoids.

By the construction and arrangement of 10 parts herein disclosed the projection of direct upward rays from the lamp is practically eliminated and all of the upper rays are caused to be reflected downwardly by the upper surface while the rays below the 15 center of the lamp are likewise projected at or below a horizontal plane by reflection from the parabolic surface and the inclined lower face.

In order to fully secure the desirable 20 functions just described, the parabolic reflector 21 may be formed elliptical or oval, with its longer axis in a plane longitudinally of the cone.

It will be seen that the invention presents 25 a very simple, efficient, and economically manufactured form of reflector adapted for general application and constructed to prevent the direct upward projection of light rays from an illuminating means disposed at the apex of the conical structure.

While the specific details of construction and the lines of projection of the light rays have been herein shown, still the invention is not confined thereto as changes and alterations may be made without departing 35 from the spirit of the invention as recited in the following claims.

Having thus described my invention, what 40 I claim as new and desire to secure by Letters Patent is:

1. A headlight reflector comprising a

body formed as an oblique cone having in vertical longitudinal section its upper element disposed in a substantially horizontal plane and its lower element inclined downwardly therefrom, said body being provided with means to support a lamp adjacent to the upper element and also being provided with a curved reflecting surface depending from the contour of the plane of the inner face of the lower element and in alignment with the source of light.

2. A head light reflector comprising a body formed as oblique cone having in vertical longitudinal section its upper element disposed in a substantially horizontal plane and its lower element inclined downwardly therefrom, said body being provided with means to support a lamp adjacent to the upper element and also being provided with a parabolic reflecting surface of elliptical outline with its longer axis longitudinally of the body and disposed in said lower element in alignment with the source of light to reflect rays outwardly from said surface in a parallel group.

3. A headlight reflector comprising a body formed as an oblique cone having in vertical longitudinal section its upper element disposed in a substantially horizontal plane and its lower element inclined downwardly therefrom, said body being provided with means to support a lamp adjacent to the upper element and also being provided with a concave parabolic reflecting surface 70 depressed from the contour of the plane of the inner surface of the lower element of the body to reflect rays outwardly therefrom in a parallel group.

In testimony whereof I affix my signature.

FERDINAND PIASZEK.
